(57) **CLAIM**

An ornamental design for a loose material scoop board, as shown and described.

DESCRIPTION

FIG. 1 is a top view of a loose material scoop board in accordance with the present invention;

FIG. 2 is a rear view of the loose material scoop board of FIG. 1;

FIG. 3 is a bottom of the loose material scoop board of FIG. 1;

FIG. 4 is a left side view of the loose material scoop board of FIG. 1;

FIG. 5 is a right side view of the loose material scoop board of FIG. 1;

FIG. 6 is a front view of the loose material scoop board of FIG. 1;

FIG. 7 is a top perspective view of the loose material scoop board of FIG. 1; and,

FIG. 8 is a bottom perspective view of the loose material scoop board of FIG. 1.

In the drawings, the broken lines illustrate environment and form no part of the claimed design.
